BASEBALL GLOVE

Richard G. Stall, Brockton, Mass.

Application April 14, 1954, Serial No. 30,017

Term of patent 14 years

(Cl. D3—11)

To all whom it may concern:

Be it known that I, Richard G. Stall, a citizen of the United States and a resident of Brockton, county of Plymouth, and Commonwealth of Massachusetts, have invented a new, original, and ornamental Design for a Baseball Glove, of which the following is a specification, reference being had to the accompanying drawings, forming part thereof.

Fig. 1 is a rear view of a baseball glove embodying the design of my invention, and

Fig. 2 is a front view of the same;

The dominant features of my design reside in the serrated and crown-like welt seaming on the back of the glove together with the absence of seaming in the interdigital areas as shown.

I claim:

The ornamental design for a baseball glove, substantially as shown and described.
